ADRIANUS ARNOLDUS MARINUS ANTONIUS KALMEIJER, OF THE HAGUE,
NETHERLANDS

SOUND-TRANSFORMING APPARATUS

Application filed January 16, 1928, Serial No. 247,215, and in the Netherlands December 30, 1927.

This invention relates to apparatus for relative transformation of electrical and mechanical energy into sound vibrations, such as a telephone receiver or transmitter, 5 gramophone sound-box, loudspeaker, etc.

There are various types of loudspeakers and the like, the best of which is today the loudspeaker with a conical diaphragm, whether large or small, vibrated by electro-magnetic, electrostatic or electrodynamic means.

According to the well-known theory, the diaphragm must have special dimensions, a predetermined apex angle and a weight as 15 light as possible. Furthermore the diaphragm must be very stiff, and for that reason a compromise between lightness and stiffness is essential, so that a maximum effect is unobtainable.

20 Moreover, the diaphragm must move bodily, or as a whole, like a piston. At the lower frequencies this can be practically carried out; but at the mean and higher frequencies, however, a serious difficulty is encountered because the diaphragm is then subjected to undesirable deformations due to the fact that the driving point of the diaphragm has already commenced to move back while the vibration is still travelling 25 toward the edge of the diaphragm, which gives rise to an oppositely-directed vibration. This effect is more pronounced the 30 more the diameter of the diaphragm increases.

35 For these reasons the large-area diaphragms are gradually being replaced by small ones which are driven by electrodynamic means. Such loudspeakers are, therefore, very costly and not available for the 40 person of average means.

I have also discovered that a very great deal of trouble arises from the usual one-point drive, and the purpose of my invention is to provide useful means, suitable for 45 musical and other acoustic reproduction, etc., which do not possess the various drawbacks of the known types, and which may be combined with any driving or driven vibrating means, whether of electro-magnetic, electrodynamic, electrostatic, or other nature.

According to my invention, I make use of an acoustic means, member or device supported at oppositely-located points and having—in a direction across connecting lines between the said points—different natural 55 periods, and of means for exerting a vibrating force at a plurality of points situated between the opposite supporting points of the acoustic means, which vibrating means is positively connected to the acoustic means. 60

With this principle in mind, various different structural embodiments are possible, and in the further description of the invention a few of them are described and illustrated. 65

The acoustic means, as well as the vibration-exerting means, may consist of a single member or of a plurality of members; in the case of a single acoustic member and a single vibrating member, the connection between these two members must be at a plurality of points, for instance along a line. 70

The acoustic member according to the invention need not have the form of a circle but may be of any other form, provided 75 there is a possibility of connecting the driving member or members to the vibrating member or members at points or along lines situated between opposite supporting points or lines of the acoustic member, and provided the latter has different natural periods 80 at the contacting points with the vibrating member or members.

It is not strictly necessary to make the acoustic member responsive to all occurring 85 frequencies to be reproduced, as there are cases in which only a part of the said frequencies are to be reproduced in the present improved manner.

My invention relates, therefore, to acoustic devices of the kind referred to, regardless of their precise character, by which driving means or means to be driven are connected at a plurality of points or along a 90 line, etc., to an acoustic member supported at either side at some distance from the connecting points, line or lines or the like.

It will be apparent from the foregoing that, according to the invention, the acoustic member is clamped or otherwise supported 100

in tensioned or untensioned condition at those points where the nodal points of the various natural periods are situated, and that it is connected at points therebetween (where the vibration loops are situated) to the driving or driven member exerting the vibrating force. In a practical embodiment, these connecting or excitation points are located midway the opposite supporting points; but they may, however, be located at other places between the supporting points, for instance at $\frac{1}{4}$ — $\frac{3}{4}$ of the total distance from one of the supporting points.

The acoustic member may be directly or indirectly connected to one or more driving members or to one or more driven members for the purpose of delivering or receiving vibration energy.

The connection of the driving member or of the member to be driven to the acoustic member may be effected in various ways, for instance, along a series of points or a single line; the driving force may be applied directly or indirectly by means of an electromagnetic or electrodynamic device such as an armature or other vibratory member, through the intermediary of a cone, a cylinder or other means, provided it is connected to the acoustic member.

30 The acoustic member according to the invention may consist of a flat or curved plate or disk clamped or otherwise supported at its circumference at different distances from one or more connecting points or from a connecting line within its said circumference; and this plate, between its circumference and the aforesaid line, is connected to the edge of a cone, an excitation coil or other driving member, or member to be driven, or vice versa. It may, alternatively, be secured at equal distances from the connecting point or points or connecting line; and it may, at different points, be of different thicknesses, tensions or materials.

45 The acoustic member may further consist of a single part or a plurality of separate or interconnected parts, the tension or the driving point of which may be adjustable for the purpose of regulating the natural periods; and for the same purpose, the pressure or the tensile stress, or both, exerted on the acoustic member by the driving member or the member to be driven may be adjustable.

55 The said member may be constructed as an ordinary or truncated straight or oblique cone which, at the edge or wide end and at the top or narrow end, is clamped in place or otherwise supported, and is connected at different points of its surface to a second cone, a cylinder or other member receiving or delivering the vibrating forces, or vice versa.

In order to obtain the same speed of translation of the acoustic frequencies, the

driving member or the member to be driven is preferably made of the same material as the acoustic member.

The single acoustic member or the multi-part acoustic member may be manufactured and sold separately, and then mounted so as to be supported along the nodal points of different natural periods and to be energized at the locus of the vibration loops for delivering or receiving energy, or vice versa. Moreover, such member need not be driven just midway between the nodal points at which it is supported, clamped or otherwise attached, but may be driven at other places where vibration loops are formed.

The improved acoustic member may be constructed in various ways. For example, if a tone range is desired extending from 3233 to 4138 vibrations per second, then an acoustic member may be used which is obtained by tracing on a suitable sheet of paper or the like two eccentric circles, one lying free within the other, and cutting away the parts located outside the part bounded by the said circles to such an extent that the ring thus formed may be clamped or supported along the circles. Thus each radius of this ring has another natural period. If desired, predetermined tones may in this way be reproduced in a more or less pronounced manner by making the sector of the acoustic member concerned relatively too small or too large, or by removing it or damping it, or by giving it more or less tension. A similar result may be obtained by clamping the acoustic member at different points in adjustable manner or by constructing it of a plurality of parts which are then permanently connected to the single driving or driven member, or to the multi-part driving or driven member, and they may individually be fastened in place and tuned so as to deliver their energy to a suitable acoustic member according to the correct tone curve.

The number of octaves desired to be reproduced may be divided into frequency series, each of which series is reproduced by a separate acoustic member. The different acoustic members may be arranged or directed in various ways in order that the reproduction of predetermined harmonics may be taken into account in obtaining a rich sound composed of fundamental notes, harmonics, overtones, etc.

A very good result may be obtained if the material of the acoustic member, as regards its nature, is suited to that of the driving or driven member, so as to harmonize the speed of the mainly-longitudinal waves in the driving member with the speed of the transverse resonant waves in the acoustic member. The same material might advantageously be used for both.

The supporting means, i. e., the clamping

means for the acoustic member, may be made heavier or lighter than the said member itself according to the construction used and its purpose. Taking into account the acoustic requirements, the acoustic member may be driven at a plurality of separate points, wherefore it can be given a very large surface area; and it is also possible to drive one and the same acoustic member by a plurality of differently or correspondingly energized driving members, which may be advantageous in some cases. The acoustic member may then be supported or damped according to the series of nodal points arising.

Conversely, the acoustic member might be supported at the place where it is driven and be driven at the place where it is supported, if the circumstances will allow this. Both methods may also be combined while taking into account resonance effects.

The device according to the invention may serve also as a microphone or sound receiver, means being provided for influencing the acoustic member between its supporting points by spoken sound or in some other manner; a plurality of electromagnetic or other receiving or transmitting devices according to the invention may be connected in parallel or in series.

Finally, the acoustic member, which, as stated, can be placed on the market separately, may have the form of a truncated cone or other suitable shape and may or may not be equipped with means for connecting it to one or more driving members, or it may simply have marks for indicating the points of connection to one or more driving or driven members.

The invention will be more fully understood with reference to the accompanying drawings, illustrating various embodiments thereof, by way of example, in a more or less diagrammatic manner.

Figure 1 is a vertical section of one form of the device or apparatus according to the invention;

Fig. 2 is a modification thereof;

Fig. 3 is an elevation of the device represented in Fig. 2;

Fig. 4 is a vertical section of another modified construction;

Fig. 5 is an elevation of Fig. 4;

Fig. 6 is an elevation of a special embodiment;

Fig. 7 illustrates still another embodiment;

Fig. 8 is a face view of a device having an oval acoustic member;

Fig. 9 is a perspective view of a device for effecting excitation by linear vibrating means;

Fig. 10 is a face view of an acoustic member divided into a plurality of sectors;

Fig. 11 is a vertical section of a receiver to be used as part of a horn speaker or of an ear-phone, constructed in accordance with the invention;

Fig. 12 shows a gramophone sound-box embodying the invention;

Fig. 13 shows a microphone or transmitter constructed according to the invention.

According to Fig. 1, the acoustic member comprises a cone 1 of paper, thin wood, celluloid or any other suitable material, such as that frequently used in making ordinary loudspeaker diaphragms, which cone may be pointed or, as shown, may be truncated and supported by a rigid arm 2. The edge of the cone is clamped in a rigid ring 3 contacting therewith along a line.

At the middle of its generatrices, the cone 1 is connected along the line 7 to and driven by a vibrating cone 4 connected by means of a rod 5 to an electromagnetic or other vibration- or oscillation-producing device 6. The material of the two cones is so chosen as to be in harmony with the speed of the vibrations or oscillations of the driving cone 4 which are mainly longitudinal, and with the speed of the resonant transverse vibrations of the acoustic member or cone 1. The thickness of the cone 1 increases circumferentially from the top downwardly according to the desired series of natural periods. The device may be so constructed that the cone 4 forms a vibrating member which is supported in a novel manner by the acoustic member.

Figs. 2 and 3 differ from Fig. 1 merely in that the cone 1¹ has its axis disaligned from that of cone 4, the latter being of right-circular form, as before, whereas cone 1¹ in this instance is oblique. The driving line is indicated at 7.

In Figs. 4 and 5, radial lines 8 are traced on the flat, or almost flat, acoustic member 1² at either side of the circular driving line 7; the angular distances between successive lines being equal, while the length of every second succeeding line is doubled according to the chosen number of octaves at the left and right of the axis of symmetry 9. The lines 10 and 11, along which the acoustic member is bounded and fixed surround the corresponding curved margins of screens 12, 13, while the vibrating or oscillating device 6 is located inside the driving cone 4. The screen 13 may be used as a baffle board.

The embodiment according to Figs. 6 and 6^a is adopted when the thickness of the acoustic member 1³ decreases stepwise along the connecting line 7 in accordance with the various frequencies to be reproduced. Moreover, the constructions shown in Figs. 5 and 6 may depart from the flat shape, and each octave curve may be accurately constructed by subdividing the sector concerned and by giving the construction lines the correspond-

ing lengths, taking into account variations which may be eventually desired.

Fig. 7 illustrates how the invention may be applied to a cylindrical acoustic member 1⁴ of constant thickness by connecting a vibrating diaphragm 14 to the said member along the circumferential line 7, and securing the nonparallel edges 15 of the cylinder in some suitable manner not shown. The active lengths of the generatrices are proportional to different natural periods. The thickness of the material is assumed to be constant in Figs. 2—5 and 7—10.

Fig. 8 shows an oval acoustic member 1⁵ vibrated along a closed connecting or driving curve 7; such member being clamped at 16 along a straight line and at 17 along a curve. Moreover, the curved driving line 7 need not be a circle but may have other forms, as in Figs. 8 and 9.

Fig. 9 shows a flat acoustic member 1⁶ of constant thickness clamped along curved lines at the top at 18 and at the bottom at 19, and vibrated midway these curved lines at a series of points located on the driving line 7 by means of a driving or driven unit mounted in a suitable box 20. In this arrangement the circular driving line has been developed to form a straight line. This embodiment may also be used for transmitting sound.

In Fig. 10, the acoustic member 1⁷ is shown as comprising a plurality of substantially-triangular sectors which are vibrated along the driving line 7 and are supported by the arm 2 and ring 3, to which latter they have a suspension connection by means of adjustable bolts 3¹ which enable the tension of said sectors to be regulated individually.

In all these embodiments, the vibrating drive may be either positive or negative, or a combination thereof, and may be effected by pressure or tensile stress or both.

Fig. 11 illustrates the application of the invention to an ear-phone or to a telephone receiver for a horn-speaker. 22 is a suitable acoustic member having different thicknesses which increase circumferentially from the top downwardly, and which is supported at 23 and 24 and vibrated by a cone 25 which, by means of an iron armature, is under electromagnetic influence.

Fig. 12 shows the invention applied to a gramophone sound-box. The stylus bar 27 vibrates the cone 25 which is connected at 7 to an acoustic member 22 supported at 23 and 24 and shaped as in Fig. 11.

Finally, Fig. 13 shows a transmitter comprising an acoustic member 1 as in Fig. 1, but designed to be activated by spoken sound and connected at 7 to a vibrating cone 4 for altering the capacity of a small condenser 28 which, by means of connecting terminals

29, may be inserted in an electrical oscillation circuit.

Besides the embodiments shown and described, various other embodiments are possible which are all based on the principle of the invention.

I claim:

1. Apparatus for effecting transformation of electrical and mechanical energy into sound vibrations, comprising resonant acoustic means supported at oppositely-located places and having, in a direction across connecting lines between the said places, different natural periods; and means connected to the acoustic means for exerting a vibrating force thereon at a plurality of points located between said oppositely-located places of the resonant acoustic means. 75

2. Apparatus for effecting transformation of electrical and mechanical energy into sound vibrations, comprising a resonant acoustic member supported at oppositely-located nodal points of natural vibrations; said member having, in a direction across connecting lines between such points, different natural periods within the acoustic range; and means connected to the acoustic member for exerting a vibrating force thereon at a plurality of vibration loop-forming points between said nodal points. 80

3. Apparatus for effecting transformation of electrical and mechanical energy into sound vibrations, comprising a resonant acoustic member supported along two circular lines, one circle within the other; said member having, in a direction across connecting lines between such circles, different natural periods within the acoustic range; and means positively contacting with the acoustic member for exerting a vibrating force thereon. 100

4. Apparatus for effecting transformation of electrical and mechanical energy into sound vibrations, comprising a resonant acoustic member supported along two curved lines, one within the other; said member having, in a direction across connecting lines between such curved lines, different natural periods within the acoustic range; and means positively contacting with the acoustic member for exerting a vibrating force thereon. 110

5. Apparatus according to claim 3, in which the force-exerting member is positively connected to the acoustic member 120 along a circular line.

In testimony whereof I affix my signature.

ADRIANUS ARNOLDUS MARINUS
ANTONIUS KALMEIJER.
